Atty's.

UNITED STATES PATENT OFFICE.

CLAUDE EVERETT STREET, OF BRADENTOWN, FLORIDA, ASSIGNOR TO FLORIDA GRAPE-
FRUIT CANNING COMPANY, INC., OF BRADENTOWN, FLORIDA, A CORPORATION OF
FLORIDA.

CRUSHER.

Application filed August 26, 1922. Serial No. 584,498.

To all whom it may concern:

Be it known that I, CLAUDE E. STREET, a citizen of the United States, and resident of Bradenton, in the county of Manatee, in the State of Florida, have invented certain new and useful Improvements in Crushers, of which the following is a specification.

My present invention relates to a machine for crushing any substance, and more particularly to a device which is readily adaptable for the crushing of citrus fruit, where it is desired to extract the juice therefrom.

The primary object of my invention is the provision of instrumentalities whereby a positive action is insured, which action may be adjustable, if desired, to crush to many degrees of fineness, and to limit the amount of juice extracted from the fruit, and which may be of an extremely simple construction.

To this end my invention includes a base upon which is slidably mounted two horizontally reciprocable jaws between which is pivotally mounted a crushing jaw, the upper portion of which is movable toward and away from each of the before mentioned jaws, such action automatically causing the reciprocable jaw toward which the crushing jaw is moving to approach said crushing jaw. Any suitable means for actuating the crushing jaw may be utilized, but I have illustrated one such means in connection with a suitable mechanism for accomplishing the above result, in the drawings, which merely illustrate one form of the invention.

In these drawings:

Fig. 1 is a side elevation partly in section.
Fig. 2 is an end elevation.

Fig. 3 is a detail of the crushing mechanism.

Referring now to the embodiment illustrated.

I have shown a base 1 upon which is mounted bearing elements 2 adapted to receive two shafts 3 and 4. The counter shaft 3 carries a disk 5. The main shaft 4 may be suitably actuated by any desired means, in this instance through pulley 6. A small gear wheel 7 on shaft 4 engages a larger gear wheel 8 on shaft 3 for the purpose of reducing the speed of the crushing jaws, the speed depending on the ratio in

size of these two gear wheels 7 and 8. A pitman 9 eccentrically mounted upon disc 5 engages the crushing jaw 10, which is pivoted to the base 1 as at 11. Opposite faces of the jaw 10 may assume a compound curve, as has been found most satisfactory. Reciprocable jaws 12 and 13 are provided engaging the base 1 as by means of a dovetail 14, to prevent accidental displacement between the base and the jaws. Each jaw is provided with a depending extension 15, which is engaged by a bar 16, having projections 17 thereon. An extension 18, of the crushing jaw 10 is positioned between the two projections 17 and reciprocates the jaws 12 and 13 by bar 16. It will thus be seen that the crushing jaw 10 moves toward jaw 12, while jaw 13 moves away from crushing jaw 10, this action compelled by bar 16, which secures a double action.

Plates 19 and 20 are secured to the reciprocable jaws and form therebetween a hopper-like cavity into which the fruit is delivered when it is desired to crush the same.

A belt 21, preferably driven from the shaft 4, operates a conveyor 22 through the sprocket 23 to remove the crushed fruit. The juice may be strained and removed from the machine by any convenient means, and I have illustrated a funnel-like structure 24 beneath the conveyor 22, to receive the juice and convey the same to any desired locality.

What I claim is:

1. A device of the character described, including a pivoted jaw member, a reciprocating jaw member, and means to cause the two jaws members to approach each other.

2. A device of the character described, including a pivoted jaw member, a reciprocating jaw member, and means whereby movement of the pivoted jaw causes movement of the reciprocable jaw.

3. The device of claim 1, said pivoted member having an extension, said extension engaging an intermediate member, said intermediate member engaging the reciprocable jaw, movement of said pivoted member causing the reciprocal movement of the jaw.

4. The device of claim 1, said pivoted member having an extension, said extension engaging an intermediate member, said in-

termediate member engaging the reciprocable jaw, movement of said pivoted member causing reciprocal movement of the jaw, said intermediate member including a 5 slide having projections thereon, the extension of said pivoted member engaging the said projections.

5. A device of the character described, including a pivoted jaw, a pair of reciprocating jaws, means to reciprocate said jaws, means to impart movement to one jaw, the pivoted jaw being located between the reciprocal jaws and under action of the movement imparting means, approaching

first one then the other of the reciprocating jaws.

6. A device of the character described, including a pair of reciprocable jaws, a pivoted element therebetween adapted to approach first one and then the other reciprocal jaw, and means to cause a reciprocable jaw to bodily approach the pivoted element when the latter swings toward the former.

In testimony whereof, I affix my signature.

CLAUDE EVERETT STREET.
